UNITED STATES PATENT OFFICE.

THOMAS P. SHEEHAN, OF NORWICHTOWN, CONNECTICUT.

TRUMPET-DRIVE MEANS FOR CARDING MACHINES.

Application filed August 30, 1922. Serial No. 585,974.

To all whom it may concern:

Be it known that I, THOMAS P. SHEEHAN, a citizen of the United States of America, and a resident of Norwichtown, in the county 5 of New London and State of Connecticut, have invented certain new and useful Improvements in Trumpet-Drive Means for Carding Machines, of which the following is a specification.

10 This invention relates to trumpet drive means for carding machines, and more particularly to that class of cards wherein the side draw is preferably used.

An object of the invention is to establish 15 a constant speed relation between the doffer comb and the trumpet, whereby a uniformity of delivery of the stock from the doffer roll to the trumpet is ensured, and a uniformity of twist may be given to the stock as it 20 passes through the trumpet.

It is a further object of the invention to eliminate the well known and unsatisfactory trumpet drive belt, and operate the trumpet by or through the same means that actuates 25 the doffer comb.

It is a further object of the invention to accomplish the above results in such a simple and efficient manner that it may be applied to existing types of side draw mechanism 30 with but little change or addition thereto.

An object of the invention is to so construct and arrange the trumpet driving devices that if need be, the speed ratios between said trumpet and the doffer comb may 35 be changed, or adjusted, to suit the class of stock operated upon and uniformity maintain that speed ratio constantly.

Heretofore in side draw devices of this class the doffer comb has been driven through 40 devices operated by a belt from the fancy shaft while the trumpet has been driven directly by a belt from the main cylinder shaft.

This arrangement is very unsatisfactory 45 because of the fact that a constant uniform speed ratio cannot be maintained between the comb and the trumpet, due to the use of two belts driven from separate sources.

It is a well known fact that it is practically impossible to maintain constant and uniform tension on the two belts and consequently slippage is apt to occur in one and not in the other, and the reverse is apt to occur at unexpected times.

50 So, too, if speed ratio between the comb and trumpet had to be changed, it necessi-

tated a change of pulley and belt for one or the other, and in the case of the trumpet drive the operation is laborious as the pulley therefor on the main cylinder shaft is extremely difficult of access.

Furthermore the breakage of belts is another bad feature to contend with, which the present invention reduces one half.

The improved trumpet drive requires the 65 use of but one belt which is at present used to drive the doffer comb and which in turn is generally driven from the fancy.

The invention further consists in certain 70 novel features of construction and arrangement of parts which will be fully understood from a description of the drawings and the claims hereinafter given.

Of the drawings.

Figure 1 represents a sufficient portion of 75 a carding machine to enable the invention to be understood.

Figure 2 a portion of the machine viewed from the side opposite to Figure 1.

Figure 3 a view looking towards the right 80 Figure 1.

Figure 4 a top plan view of Figure 3.

Figure 5 a section on the line 5—5 Figure 3.

Figure 6 a section on the line 6—6 Figure 85 3.

Figure 7 a section on the line 7—7 Figure 6.

Figure 8 a diagram view showing means to drive the trumpet directly from the doffer 90 comb shaft.

Like characters represent like parts throughout the several figures of the drawings.

Referring to the drawings:

The drawings herewith show a sufficient portion of one form of card to illustrate the application of the invention, but it will be understood that it is not the intention to limit the invention to the exact construction 100 and arrangement herein shown as the same might be changed without departing from its spirit and scope.

As far as is known, in side draw mechanism of this class, means to drive the trumpet by or through the comb drive devices, whereby a uniformity of speed ratio is maintained there between, has never been used, and therefore it is the intention to claim broadly, means to drive a trumpet at the 105 desired speed ratio, uniformly with the doffer comb.

In the present instance it is desirable to use existing devices as far as possible so that the invention might be applied to cards at present in use at the least expense.

5 The drawings show a frame 10 which in practice suitably supports the several cylinders and rolls among them being a main cylinder 11 a doffer cylinder 12 and a fancy 13. These are or may be driven in any 10 usual or suitable manner not deemed necessary to show.

The doffer comb shaft 14, which supports the comb 15, is mounted in bearings in a casing 16, and a bracket 17, entering said 15 casing, which encloses the bifurcated lever 18 fast to said shaft and the actuating crank 19 therefor. Said crank 19 has loose thereon the block 20 which engages said lever 18 and imparts vibratory movement thereto when 20 the crank revolves. The shaft 21 of which the crank 19 is preferably a part, has fast at one end thereof the pulley 22 driven from the fancy 13 by the belt 23.

The structure above described is such as 25 is used in certain side draw devices.

In the present instance the shaft 21 is extended across the machine and finds a bearing in the bracket 17, adjacent which it has fast thereon a worm 24 in mesh with a worm 30 gear 25 fast on a short shaft 26 suitably supported in bearings 27.

The draw rolls 30 and 31 see Figures 2, 3, 4, 6 and 7, have gears 32, 33, fast therewith and are driven in the proper direction and 35 speed by means of the gear 34 meshing with gear 33, said gear 34 being in turn driven from any usual or suitable source not shown.

The trumpet 35 through which the stock is drawn by the rolls 30 and 31 is suitably 40 revolvably mounted in a bearing 36 and held from longitudinal movement therein by the collars 37 and 38.

Fast with the trumpet 35 is a worm gear 39 meshing with a worm 40 on the shaft 26. 45 From the foregoing it will be seen that the doffer comb 15 and trumpet 35 are driven from the same source and consequently the speed relation between the two must be constant.

50 It will also be observed that but very slight change or addition has to be made to existing devices to obtain the advantages of the present invention.

The above described device is the preferred 55 form but it is obvious that the drive therefor may be derived from any convenient source other than the fancy if desired.

The diagram view Figure 8 shows another 60 form wherein the vibrating comb shaft 14^x has an arm 45 fast therewith to which a link 46 is pivoted at one end while the other is pivoted to an extension 47 of a friction clutch member 48. Said clutch consists of a ring 49, fast with the trumpet 35, which is 65 surrounded by the member 48, between

which spring pressed pins 50 are mounted in cam shaped notches of said member 48.

Movement of arm 45 in direction of arrow *a* will impart movement to clutch member 48 causing the pins 50 to wedge between the cam notches and ring 49 and turn the trumpet 35. Movement of the arm 45 in the opposite direction causes release of said pins and no movement to the trumpet.

The vibratory movement of the comb shaft 75 14^x is extremely rapid while the rotary movement necessary for the trumpet is very much less, the difference in some instances being as much as 11 to 1.

In order to vary the relative movement 80 between the comb and the trumpet the arm 45 is slotted so that the link 46 may be adjusted thereon to give greater or less throw to the clutch member 48.

In the form just described the relative 85 movement between the comb and trumpet may be regulated by a change in one of the worms 24 or 39 or both if so desired.

Having described the invention I claim:

1. In a carding machine of the class described, a doffer cylinder; a doffer comb; means operated by said machine to actuate said comb; a trumpet; and means including said comb actuating means arranged to drive said trumpet. 90

2. In a carding machine of the class described, a doffer cylinder; a doffer comb; means operated by said machine to actuate said comb; a trumpet; and means including said comb actuating means to drive said trumpet in fixed timed relation to said comb. 100

3. In a carding machine of the class described, a doffer cylinder; a doffer comb; means operated by said machine to actuate said comb; a trumpet; and means including said comb actuating means intermediate said comb and said trumpet to drive said trumpet. 105

4. In a carding machine of the class described, a doffer cylinder; a doffer comb; means operated by said machine to actuate said comb; a trumpet; and means including said comb actuating means to drive said trumpet at different speeds in timed relation to said comb. 110

5. In a device of the class described, a doffer cylinder; a doffer comb; means including a shaft to impart vibratory movement to said comb; a trumpet; and means to impart rotary movement to said trumpet in fixed timed relation to said comb, said means receiving its motion from said vibratory movement means. 115

6. In a device of the class described, a doffer cylinder; a doffer comb; a second shaft; means to drive said second shaft; means coacting with said second shaft to impart vibratory movement to said comb; a trumpet; means carried by said trumpet and adapted to impart rotary motion thereto; and means moving in unison with said 120 125 130

- comb and adapted to actuate said last mentioned means to drive said trumpet.
7. In a carding machine of the class described, a doffer cylinder; a doffer comb 5 adapted to be vibrated at high speed; a shaft; means operated by said machine to drive said shaft; means including a vibrating shaft coacting with said shaft to impart vibratory movement to said comb; a trumpet adapted to be rotated at a relatively 10 low speed; and means intermediate said vibrating shaft and said trumpet adapted to impart rotary movement to said trumpet, said means including a friction clutch.
8. In a device of the class described, a doffer cylinder; a doffer comb; a rotary 15 shaft provided with means to impart vibratory movement to said comb; means to drive said shaft; a trumpet; and link and lever 20 connections between said comb and said trumpet and adapted to utilize the vibratory movement of said trumpet.
9. In a device of the class described, a doffer cylinder; a doffer comb; means to cause a vibratory movement to said comb; a trumpet; a clutch adapted to cause rotation of said trumpet in one direction; and means whereby the vibratory movement of said comb will cause actuation of said clutch and trumpet.
10. In a device of the class described, a doffer cylinder; a doffer comb; means to cause vibratory movement to said comb including a rock shaft; a trumpet; a friction clutch lever carried by said trumpet; a lever fast 35 with said rock shaft; a link connecting said levers and adapted to transmit motion from said rock shaft to said clutch lever; and means to adjust said link whereby the speed of said clutch lever may be regulated.

Signed by me at Boston, Mass. this 4th day of August, 1922.

THOMAS P. SHEEHAN.
